2,341,243

WAVE LENGTH MODULATION

Robert E. Schock, Riverhead, N. Y., assignor to
Radio Corporation of America, a corporation
of Delaware

Original application July 18, 1940, Serial No.
346,079, now Patent No. 2,310,260, dated Febru-
ary 9, 1943. Divided and this application Feb-
ruary 27, 1942, Serial No. 432,609

4 Claims. (Cl. 179—171.5)

This application describes a method of and means for balancing out the amplitude modulation, which is often impressed on a carrier wave at the time it is being wave-length-modulated, and is a division of my United States application No. 346,079, filed July 18, 1940, now U. S. Patent # 2,310,260, dated February 9, 1943.

In describing my invention, reference will be made to the attached drawings wherein:

Figs. 1, 1a, 2, and 2a each illustrate a wave length modulator with wave amplitude modulation compensating means.

An arrangement of my novel means to produce wave length modulation of wave energy and at the same time correct inherent amplitude modulation thereof will now be described.

In the circuit of Fig. 1 tube 90 is an oscillator tube having its anode 92, grid 94, and cathode 96 coupled in regenerative circuits comprising an inductance 100, a variable capacity 102, and a resistance 104 shunted by a condenser 106. The elements 100 and 102 comprise the tank circuit and the elements 104 and 106 comprise the condenser and grid leak of a Hartley oscillator circuit. The radio frequency plate circuit of the oscillator is coupled to the anode 110 of a reactance modulator tube 112, through blocking condenser 114. The anode 110 of the reactance tube is coupled to the cathode 116 by a coupling condenser C, resistance R, and a second condenser C1. This last circuit comprises the phase shifting circuit of the reactance tube modulator. The grid 118 is connected to a point on this phase shifting circuit to be excited by a voltage displaced in phase by about 90 degrees relative to the radio-frequency voltage on plate 92 of the oscillator tube 90.

By controlling the conductance of the reactance tube 112 the reactive effect therein is controlled to control the tuning of tank circuit 100, 106. This is done by modulating potentials from 120. The operation of this type of wave length modulator is now well understood, and additional description here is believed unnecessary.

The oscillator feeds an amplifier tube 50 by way of a coupling and blocking condenser 54, and the plate circuit 55 of tube 50 is, in this case, tuned to the oscillator frequency.

Potentiometer 120 is a means of controlling the modulation input voltage to the reactance modulator tube 112, and potentiometer 112 is a means of controlling the amount of modulation voltage fed to the control grid 49 of amplifier tube 50 for the purpose of producing amplitude modulation and thereby removing undesired amplitude mod-

ulation which is introduced on the signal during the frequency modulating process.

In operation, a modulating voltage impressed on the control grid 118 of tube 112, Fig. 1, causes a modulation of the wave length of the oscillator including tube 90. It has also been found that when the conductance of the reactance tube 112 is increased by any instantaneous value of modulating voltage, the oscillator output is at the same instant somewhat diminished, and vice versa. If, at the same instant, a portion of the modulation voltage—same polarity—is fed to the control grid 49 of amplifier tube 50 from potentiometer 122 as shown in Fig. 1, the gain of this amplifier will increase when the oscillator output is decreasing and vice versa. The amount of this change of gain may be so adjusted that complete compensation is made for the amplitude modulation present.

In Fig. 1a, the compensating modulation voltage is supplied from a transformer 60 to the two potentiometers 120 and 122. Modulation potential of one phase is supplied to the grid 118 of reactance tube 112 as in Fig. 1. Here, however, the compensating modulation potential is supplied to the grid 113 of a tube 111 the anode of which is connected to the anode 97 of the tube 90 and to a common plate potential supply choke 117. In this manner, the oscillator tube 90 is plate-modulated in a direction to oppose undesired amplitude modulation thereof during the wave length modulation process accomplished by the reactance tube 112.

The circuit of Fig. 2 is similar to that of Fig. 1 except for the method of obtaining compensating or balancing voltage to apply to the grid of amplifier tube 50. Here the amplitude modulation on the signal is detected in rectifier 80, and this detected audio voltage is applied across potentiometer resistance 70', and from 70' a voltage is impressed on the grid 49 of tube 50 and used for compensation. In Fig. 2 the detector tube 80 is transformer-coupled by the windings of circuits 85 and 86 to the amplifier tube 50, and the detected audio voltage filtered in circuit 81 to remove radio-frequency components is fed to potentiometer 70'.

The modulator of Fig. 2 may be modified as shown in Fig. 2a. In this modification, tube 111 has its grid 113 coupled to a point on resistance 70' to be excited by the compensation control potential. Tube 111 amplifies the control potential and derives its plate current from choke 117 which also supplies plate current to the plate of the oscillator tube 90. The oscillator is plate-

modulated to amplitude modulate the oscillations in a direction to compensate amplitude modulation thereof in an undesired manner during the frequency modulation process.

What is claimed is:

1. In a wave length modulation system, an oscillation generator comprising an electron discharge device having its electrodes connected in oscillation generating and frequency determining circuits, a reactance tube having electrodes connected in shunt to a portion at least of said oscillation generating circuits, said reactance tube having two electrodes excited in phase displaced relation by generated oscillations whereby said tube is caused to act as a reactance forming part of said oscillation generating circuits, an oscillation amplifier tube having input electrodes coupled to said oscillation generating circuits and having output electrodes coupled to an output circuit, and connections for modulating the impedance of said reactance tube and the impedance of said amplifier tube in accordance with control potentials.

2. In a wave length modulation system, an oscillation generator comprising an electron discharge device having its electrodes connected in oscillation generating and frequency determining circuits, a reactance tube having electrodes connected in shunt to a portion at least of said oscillation generating circuits, said reactance tube having two electrodes excited in phase displaced relation by generated oscillations whereby said tube is caused to act as a reactance forming part of said oscillation generating circuits, a radio frequency amplifier tube having input electrodes coupled to said oscillation generating circuits and having output electrodes connected in an output circuit, and connections for modulating the gain of said reactance tube and the gain of said amplifier tube in accordance with control potentials.

3. In a frequency modulation system, an oscillation generator comprising an electron discharge device having its electrodes connected in oscillation generating and frequency determining circuits, a reactance tube having an anode and a cathode connected to spaced points on said oscillation generating circuits, said tube having a control grid coupled to said generating circuits and excited by generated oscillations in phase displaced relation with respect to the excitation of said anode by said generated oscillations whereby said tube is caused to act as a reactance

forming part of said oscillation generating circuits, a relay tube having an anode and having a control grid and cathode coupled to said oscillation generating circuits, an output circuit coupled to the anode and cathode of said tube, and connections for modulating an electrode in said reactance tube and an electrode in said relay tube by modulating potentials.

4. In a timing modulation system, a first tube having electrodes including an anode and a cathode coupled to a tuned circuit wherein wave energy to be modulated flows, the tuning of said circuit determining in part at least the timing of the wave energy flowing in said tuned circuit, a reactance tube having an electron receiving electrode, a cathode, and a control electrode, connections for impressing voltages from said tuned circuit on the electron receiving electrode of said reactance tube, connections for impressing voltages from said tuned circuit on the control electrode of said reactance tube, said impressed voltages being displaced substantially 90 degrees, whereby a reactive effect is produced in said reactance tube, connections coupling the impedance between two electrodes of said reactance tube to said tuned circuit to supplement the reactance of the tuned circuit by the reactance of said reactance tube, a source of modulating potentials arranged to modulate the potential on an electrode of said reactance tube in accordance with the modulating potentials to thereby modulate the gain of the reactance tube and modulate the supplemental reactance supplied to said tuned circuit to modulate the timing of the wave energy flowing therein, and means for compensating for amplitude modulation produced during said timing modulation comprising a modulation potential amplifier tube having an anode, a cathode and a control grid, a modulation potential impedance coupling the anode of said amplifier tube to the cathode of said amplifier tube, an impedance to wave energy of the frequency of the wave energy to be modulated coupling the anode of said amplifier tube to the anode of said first tube, a coupling between the cathode of said amplifier tube and the cathode of said first tube, and connections to the control grid and cathode of said amplifier tube for impressing thereon potentials which vary substantially in accordance with said modulating potentials and substantially in phase opposition thereto.

ROBERT E. SCHOCK.
